UNITED STATES PATENT OFFICE.

JOHN W. KOHLHEPP, OF CHICAGO, ILLINOIS, ASSIGNOR TO ALLBRIGHT-NELL COMPANY, OF CHICAGO, ILLINOIS, A CORPORATION OF ILLINOIS.

METHOD AND MACHINE FOR CLEANING CARCASSES IN GROUPS.

1,367,055.

Specification of Letters Patent.

Patented Feb. 1, 1921.

Application filed July 15, 1919. Serial No. 310,971.

To all whom it may concern:

Be it known that I, JOHN W. KOHLHEPP, a citizen of the United States, and a resident of the city of Chicago, in the county of

5 Cook and State of Illinois, have invented certain new and useful Improvements in Methods and Machines for Cleaning Carcasses in Groups; and I do hereby declare that the following is a full, clear, and exact description of the same, reference being 10 had to the accompanying drawings, and to the numerals of reference marked thereon, which form a part of this specification.

This invention relates to a carcass cleaning machine wherein flexible and rigid massaging mechanisms are adapted to successfully clean carcasses in groups, in which the added pressure produced by the accumulated weight of the plurality of carcasses facilitates 15 cleaning thereof and causes the massaging mechanisms to do more efficient work.

It is an object of this invention to provide a carcass dehairing machine adapted to clean carcasses in groups.

20 It is also an object of the invention to provide a carcass cleaning machine wherein a plurality of carcasses are adapted to coact on each other to facilitate cleaning as they are being acted upon by rotatable scraping mechanisms.

25 A further object of the invention is the construction of a carcass cleaning machine wherein a plurality of carcasses are adapted to be simultaneously cleaned by delivering the same in quantities into the field of operation of rotatable scraping drums one of which is adapted to be stopped independently of the other to permit discharge of the carcass between the drums when said carcasses have been sufficiently cleaned.

30 It is a further object of this invention to provide a carcass dehairing machine wherein a plurality of carcasses rub and scrape one another as they are acted upon by rotatable dehairing mechanisms.

35 Another object of the invention is the construction of a carcass cleaning machine having a plurality of independently operable sets of rotatable scraping drums, each 40 set of said drums adapted to clean a number of carcasses, and further capable of having one of the drums thereof stopped to permit

discharge of the carcasses between the drums, while the other sets of drums are still in operation.

55

It is furthermore an object of this invention to provide a carcass cleaning machine wherein the added weight of a plurality of carcasses delivered into the field of operation of independently rotatable scraping 60 wheels, acts to increase the cleaning efficiency of the machine.

Another object of the invention is to provide a method of cleaning carcasses by delivering a number of carcasses into the field 65 of operation of cleaning wheels so that the added weight of the carcasses will raise the cleaning efficiency of the machine.

It is an important object of this invention to provide a carcass dehairing machine adapted to simultaneously clean a plurality of groups of carcasses disposed in the field of operation of sets of rotatable dehairing drums, each group of carcasses adapted to be discharged from the machine independently or simultaneously with the other 75 groups by stopping certain of the drums.

Other and further important objects of the invention will be apparent from the disclosures in the specification and drawings.

80

The invention (in a preferred form) is illustrated in the drawings and hereinafter more fully described.

On the drawings:

Figure 1 is a side elevation of a carcass 85 dehairing machine partly broken away and embodying the principles of this invention.

Fig. 2 is a top plan view thereof partly broken away.

Fig. 3 is a fragmentary top plan view of a 90 portion of the machine broken away to show the discharge chute or grate, and a portion of a conveyer.

Fig. 4 is a detail view taken on line 4-4 of Fig. 1, with parts omitted.

95

Fig. 5 is a detail end view of carcass conveying support taken on line 5-5, of Fig. 3.

Fig. 6 is an enlarged side elevation of the conveyer.

Fig. 7 is a fragmentary top view and end 100 view of the discharge chute.

Fig. 8 is an enlarged side elevation of one of the flexible scraping wheels.

Fig. 9 is a front view thereof.

Fig. 10 is a detail section taken on line 10-10, of Fig. 8.

Fig. 11 is an enlarged side elevation of one of the rigid scraping wheels.

5 Fig. 12 is a front view thereof.

Fig. 13 is a detail section taken on line 13-13 of Fig. 11.

As shown on the drawings:

The reference numeral 1, indicates a scalding vat or tank, supported by legs 2, and having an enlarged conveyer section 3, at one end thereof. The section 3, has the end thereof resting in an angle support 4, which is rigidly secured transversely on the front 15 end of a machine framework 5. Disposed adjacent one another within the tank section 3, are two inclined conveyer mechanisms each embracing a lower horizontal shaft 6, and an upper shaft 7, which is supported on 20 journal brackets 8, secured to the front of the framework 5, and above the tank section 3. Secured on the lower shaft 6, are two spaced sprocket gears 9, around which two endless chains or link belts 10, are trained. 25 The chains 10, incline upwardly toward the framework 5, and are engaged around two sprocket gears 11, secured near the ends of the upper shaft 7. One end of the shaft 7, extends beyond the side of the framework 30 5, and has secured thereon a driving sprocket gear 12, around which a driving chain 13, is engaged. The two chains 10, are secured together by a plurality of transversely disposed parallel angle bars 14, to form a carcass conveyer. Rigidly secured on each of the angle bars 14, are a plurality of lifting fingers or prongs 15, disposed adjacent one another in spaced relation. The lower parts 35 of said fingers 15, are bent at an angle and are rigidly secured to the angle cross-bars 14, by rivets 16, or other suitable means. Each of the conveyer mechanisms is independently adjustable by means of an adjusting rod 17, one end of which is attached 40 to a supporting block 18, for the lower shaft 6, while the other end of said rod 17, is threaded as at 18', and threads through a bracket member 19. The free end of the rod 17, is provided with a square head 20, to receive a tool to permit rotation of said rod to 45 move the shaft 6 toward or away from the shaft 7, to loosen or tighten the conveyer chains 10. The block 18 and the bracket 19, are supported on a conveyer supporting beam 21.

Rigidly secured to the inner sides of the two front uprights of the framework 5, are two oppositely disposed bracket plates 22, having integral inclined flanges 23, to which is bolted or riveted a receiving board or apron 24, positioned transversely across the machine below the upper ends of the conveyer mechanism. Secured to the apron 24,

are a plurality of spaced outwardly projecting fingers or prongs 25, so spaced that the 65 conveyer fingers 15, will pass therebetween when the conveyers are in operation. The apron 24, is positioned to receive the carcasses as they are conveyed from the scalding tank by means of the conveyer mechanisms. 70

Secured to the uprights of the framework 5, are a plurality of horizontal lower supporting bars or angle members 26, and upper supporting bars or angle members 27. Connected to the bars 26 and 27, near the 75 rear of the machine are vertical angle members 28. Rigidly secured in the rear portion of the framework 5, to the vertical members 28, and to the rear uprights of the framework, is an inclined discharge apron 80 or grate comprising an upper transverse beam 29, attached to the upright members 28, and a parallel lower transverse angle member 30, secured to the framework uprights. A plurality of parallel spaced inclined grate bars 31, have the ends thereof secured to the members 29 and 30. Carcasses delivered onto the discharge grate roll downwardly thereon and pass into a discharge chute or hopper 32, mounted on the 90 rear end of the machine.

As clearly shown in Fig. 2, two independent sets of dehauling or cleaning mechanisms are shown mounted adjacent one another within the framework 5, and positioned to co-act with the conveyer mechanisms to receive carcasses therefrom. Each set of the dehauling mechanisms comprises a lower cleaning device and an upper cleaning device said upper cleaning device being 100 positioned above and to the rear of the lower cleaning device. The lower cleaning device embraces a horizontal shaft 33, the inner end of which is journaled in a central bearing box 34, while the outer position is 105 journaled in an outer bearing 35. Mounted on the outer projecting end of the shaft 33, is an outer and an inner sprocket gear. Trained around the outer sprocket gear is the chain 13. The inner sprocket gear has 110 an endless chain 36, trained therearound. Formed on the shaft 33, is a cleaning drum made up of a plurality of adjacently positioned cleaning or massaging wheels each 115 embracing a rigid hub 37, a flat rigid rim 38, and radial rigid spokes 39, integrally connected between the hub and rim. Secured in offset or staggered relation on the wheel rim 38, and alternately projecting slightly beyond the opposite sides thereof are a plurality of circumferentially disposed dehauling or cleaning devices. Each dehauling device comprises a rectangular plate 40, having a cushion 41, secured to the lower surface, and a plurality of scraper 125 blades 42, secured in staggered relation on

the outer surface. The dehairing devices are secured to the wheel rim 38, by bolts 43.

The upper cleaning mechanism comprises a shaft 44, the inner end of which is journaled in a bearing 45, while the other end projects through the side of the machine and has a sprocket gear secured thereon around which the chain 36 is trained. Also mounted on the outer end of the upper shaft 44, 5 is a clutch mechanism 46, adapted to be operated by a lever 47, to stop the upper cleaning mechanism independently of the lower cleaning mechanism. Formed on the upper shaft 44, is a flexible cleaning drum 10 embracing a plurality of adjacently disposed cleaning or massaging wheels each comprising a plurality of hub members 48, secured radially on the shaft 44, and having secured thereto the inner ends of flexible spokes 49. The outer ends of the flexible spokes 49, are attached to a flexible rim 50, on which a plurality of scraper blades 51, are mounted in staggered relation.

The operation is as follows:

25 The carcasses to be cleaned are first placed in the scalding vat or tank 1, and when properly scalded are passed into the enlarged section 3, into position to be engaged by the fingers 15, of either one of the conveyors. Carcasses are thus carried upwardly out of the scalding tank by the rotating conveyors, and are deposited over the tops of the conveyors onto the inclined receiving apron 24—25. 30 The conveyors are operable independently of each other, and are each adapted to carry a plurality of carcasses from the scalding tank and deposit them into the field of operation of the rotatable cleaning drums. The drums rotate in the same direction, as indicated by the small arrows of Fig. 1, and the plurality of carcasses in the field of operation of said drums, are cleaned, massaged and rotated by the scraper blades 35 40 45 50 55 42 and 51. It has been found that when more than two carcasses are thrown into the field of operation of the rotating cleaning drums at one time, much better results are obtained than when only one or two carcasses are cleaned. The carcasses when rotated by the drums act to clean each other. The added pressure of five or more carcasses being cleaned at one time, produced by the accumulated weight of the plurality of carcasses, acts to materially increase the cleaning efficiency of the machine.

When the group of carcasses being acted upon by the cleaning drums, is sufficiently cleaned, the lever 47, is moved to operate the clutch 46, to cause the upper or flexible cleaning drum to stop, but permitting the lower drum to continue its rotation. The operation causes the lower drum to flex the

flexible rims 50, inwardly, by forcing the cleaned carcasses outwardly between the upper and lower drums, and upon the inclined discharge chute or grate 30—31. From the chute 30—31, the cleaned carcasses roll into the hopper 32, and are then removed from the machine.

70 By referring to Fig. 2, it will be noted that the machine is equipped with a plurality of sets of elevating and cleaning mechanisms, each set being independently operable of the other. Attention is also 75 called to the fact that the upper or flexible drum of each cleaning mechanism is adapted to be stopped independently of the lower or rigid drum, to permit discharge of cleaned carcasses, between the drums. The 80 rims 50, of the flexible wheels, are held in extended position by centrifugal force, when the flexible drums are rotated.

As shown in Fig. 6, the conveyers are adapted to be tightened or loosened by 85 merely rotating the adjusting rods 17, of the respective conveyers.

Particular attention is directed to the fact that the dehairing machine is adapted to receive and clean a plurality of carcasses at 90 the same time. The cleaning of carcasses in groups by means of rotatable scraping mechanisms is very efficient, for the reason that said rotatable scraping mechanisms rotate and tumble the carcasses about 95 in a common area thus causing the same to rub and scrape against each other, thereby producing a new method of cleaning carcasses more efficiently and in a comparatively short time.

100 I am aware that numerous details of construction may be varied through a wide range without departing from the principles of this invention, and I therefore do not purpose limiting the patent granted 105 otherwise than necessitated by the prior art.

I claim as my invention:

1. A method of simultaneously dehairing a plurality of carcasses which consists in applying dehairing devices to the same and 110 simultaneously causing said carcasses to rub against each other to remove the hair therefrom.

2. A method of cleaning a plurality of carcasses which consists in subjecting the 115 carcasses to the action of rotatable dehairing drums and causing the carcasses to simultaneously rub one another to assist in the dehairing process.

3. A method of simultaneously dehairing 120 a plurality of carcasses which consists in rotating the carcasses by rotatable dehairing devices whereby the added pressure caused by the accumulated weight of said carcasses increases the cleaning efficiency of 125 the devices and also causes the carcasses to

act on one another to remove the hair therefrom.

4. A method of simultaneously cleaning a group of carcasses which consists in rotating and tumbling the carcasses about in a common area by means of dehairing devices to cause the carcasses to massage, rub and scrape one another.

In testimony whereof I have hereunto subscribed my name in the presence of two 10 subscribing witnesses.

JOHN W. KOHLHEPP.
